FIREARM EXTRACTOR

Fletcher C. Speed, Kansas City, Mo., assignor to
 Remington Arms Company, Inc., Bridgeport,
 Conn., a corporation of Delaware

Application April 23, 1943, Serial No. 484,180

9 Claims. (Cl. 89—24)

The present invention relates to a firearm extractor, particularly for use in connection with a firearm of the universal receiver type adapted for use in laboratory test firing of ammunition, and which have interchangeable barrels of different calibers, so that ammunition of various calibers can be tested in the same receiver. It has been the practice heretofore to remove the fired cartridge case from the cartridge chamber by prying it loose as with a screw driver or other similar tool. In the case of removing a cartridge which has failed to fire for any reason this method of removal is apt to be very dangerous because of the possibility of accidental firing through mutilation of the cartridge case head. It is an object of the invention to provide extractor means which may be readily incorporated in the universal receiver, and which is adapted to be actuated to engage the extractor groove of the cartridge case, and to exert extracting pressure thereon to effectually disengage it from the cartridge chamber and without the possibility of mutilation and accidental firing.

A further object is to provide extractor means having interchangeable extractor plates for cooperation with the interchangeable barrels of the receiver, and which may be removed and assembled with facility for cooperation with the respective barrels of different calibers.

With the above and other objects in view, an embodiment of the invention is shown in the accompanying drawings, and this embodiment will be hereinafter more fully described with reference thereto, and the invention will be finally pointed out in the claims.

In the drawings—

Fig. 1 is a side elevation of a universal receiver provided with extractor means according to the exemplary illustrated embodiment of the invention, the parts being shown in their normal operative position with the breech of the receiver closed, and the dot-and-dash lines showing the open position of the breech.

Fig. 2 is a plan view thereof, partially in horizontal section.

Fig. 3 is an end elevation of the breech end of the receiver.

Fig. 4 is a fragmentary vertical sectional view on an enlarged scale, taken along the line 4—4 of Fig. 2.

Fig. 5 is a horizontal sectional view, with the extractor means shown in projected engaging relation to the cartridge case preparatory to extraction, the disengaged or retracted relation being shown by the dot-and-dash lines.

Fig. 6 is a similar view showing the projected extractor means in its operatively moved position to extract the cartridge case, the dot-and-dash lines showing the retracted position of the extractor plate wherein it is disengaged from the extracted cartridge case.

Fig. 7 is an end view of one of the interchangeable barrels, shown for example as of .50 caliber.

Fig. 8 is a side elevation of the rearward end of 10 the barrel.

Fig. 9 is a horizontal sectional view, taken along the line 9—9 of Fig. 7.

Fig. 10 is a side elevation of the .50 caliber extractor plate employed.

Fig. 11 is an end view thereof.

Fig. 12 is an end view of another of the interchangeable barrels, shown for example as of .30 caliber.

Fig. 13 is a side elevation of the end portion 20 of the .30 caliber barrel.

Fig. 14 is a side elevation of the .30 caliber extractor plate employed.

Fig. 15 is an end view thereof.

Fig. 16 is a fragmentary horizontal sectional 25 view, showing the receiver with the extractor plate removed, and the spring pressed plunger member retained in retracted position.

Similar reference characters indicate corresponding parts throughout the several figures of 30 the drawings.

Referring to the drawings, the firearm of the universal receiver type illustrated by way of example comprises a receiver body, indicated generally as 10, in the form of a heavy metal block, 35 of rectangular form at its rearward portion and of cylindrical form at its forward portion, provided at its lower side with a centrally disposed apertured mounting web 11 mounted for elevational adjustment of the receiver body upon a bracket 12 by means of a mounting pin 13, the bracket being supported upon a suitable bed support 14. Upon the upper side of the receiver body there is provided an accessory part receiving 40 45 slideway 15, for receiving various testing fixtures (not shown). The receiver body is provided with a horizontal barrel receiving bore 16 extending at its inner end to a vertically disposed breech block passage 17, the inner end of the bore being provided with an annular abutment shoulder 18 against which the inner ends of the interchangeable barrels are respectively engaged, as will presently more fully appear. In axial line 50 55 with the bore 16 the rearward wall of the body member is provided with a relatively large load-

ing aperture 19 extending to the breech block passage.

The removably mounted interchangeable barrel 20, illustrated for example as the .50 caliber barrel, is provided at its rearward end with a shouldered relatively large diameter chamber portion 21, adapted to fit within the bore 16 of the body member against the shoulder 18, and provided at its rearward end with a reduced diameter shouldered end portion 22, engaged within the inner reduced end of the bore 16 with its end surface in flush relation with the forward flat side of the breech block passage 17. Upon the barrel there is engaged a locking sleeve 23, adapted to fit within the bore 16 with its inner end engaging the forward end of the shouldered chamber portion 21, being provided with a relatively heavy helical thread 24 screwed into internal threads 25 provided within the bore 16, and having at its outer end a turning flange 26 provided with handle knobs 27, so that inward turning of the sleeve tightens it against the shoulder of the chamber portion 21 to secure the barrel in place. A set screw 28 is provided in the turning flange 26 and engages the barrel to secure the sleeve against turning, the barrel itself being held against turning by a key 29 secured in the receiver body and engaged in a keyway 30 provided in the chamber portion 21 of the barrel. The barrel is provided the usual rifled bore 31 and cartridge chamber 32, the entrance end of the chamber being outwardly beveled, as at 33, the cannelure or extraction groove A of the cartridge case B being disposed within this beveled portion in the normal firing position.

Within the passage 17 there is engaged for vertical reciprocatory movement the breech block 34. Upon the rearward face of the body member there is secured a bracket 35, provided with a downwardly projecting bearing portion 36 in which is engaged the breech block operative shaft 37, this shaft having secured upon it a lever 38 slidably connected to the lower bifurcated end of the breech block by means of a cross-pin 39 engaged in a slot 40 in the breech block. The shaft also has secured upon it an operating handle 41, which upon being swung between its two operative positions imparts closing and opening movement to the breech block as indicated by the respective full lines and dot-and-dash lines in Fig. 1. The open position of the breech block is determined by means of an adjustable set-screw 42, engaged in a mounting block portion 43 of the bracket 35 and adapted to be engaged by the tail portion 44 of the lever 38 in the open position of the breech block.

Upon the bracket 35 there is hingedly mounted by means of a pivot screw 45 a firing lever 46 adapted to be connected in firing relation to the firing pin carried by the breech block in the operative raised position, as shown in Fig. 1, and adapted to be fired by pulling thereon, preferably by means of a lanyard 47 connected to its upper end. As the particular structure of the firing mechanism does not constitute a part of the present invention, no further description of its details is deemed necessary.

The parts thus far described are of known construction and do not in themselves constitute part of the present invention, except insofar as they enter into cooperative relation with the extractor means of the invention incorporated in the receiver.

The end portion 22 of the barrel is provided with a milled out horizontal slideway 48 extend-

ing from the periphery at one side to the beveled entrance portion 33, within which the head of the cartridge case is disposed in firing position, the upper and lower side walls of this slideway being parallel and the vertical base wall being substantially flush with the base of the entrance portion 33, to provide a guide for the slidable extractor plate to engage the cannelure groove of the cartridge case, as will presently more fully appear.

The receiver body 10 is provided in one side with a horizontal passage 49, of rectangular cross section extending transversely from one outer side surface to the slideway 48 of the barrel, and is also provided with a cylindrical bore 50 extending longitudinally from the passage 49 to the rearward wall of the receiver. In axial line with the bore 50 there is provided a cylindrical bore 51 extending longitudinally forwardly a predetermined distance from the passage 49, a longitudinal slot opening 52 extending transversely from the outer side surface of the receiver to this bore 51.

The extractor plate 53 is of generally rectangular outline and rectangular cross-section, and is engaged within the passage 49 for lateral inward and outward movement to engage and disengage the cannelure groove of the cartridge case, and for lateral forward and rearward swinging movement to impart extraction movement to the cartridge case, as will presently more fully appear, the height of the passage 49 corresponding to the height of the plate to guide its lateral movements, while its width is substantially greater than the thickness of the plate to provide space for its lateral swinging movement. The face side of the extractor plate is beveled down, as at 54, to a reduced thickness inner end portion adapted to engage the cannelure of the cartridge, being provided for this purpose with a semi-circular recess 55, partially cylindrical and partially chamfered, as shown clearly in Fig. 11, in conformity to the shape of the cannelure groove.

Intermediate its ends the extractor plate is provided in its forward surface with a longitudinal channel slot 56 which is engaged by a key rib 57 provided upon the inner end of the cylindrical plunger 58 slidably engaged within the cylindrical bore 50, the slot being of predetermined greater length than the length of the key to thereby limit the in and out lateral movement of the plate. The plunger is provided with a reduced diameter stem portion 59 extending through an apertured cover plate 60, secured upon the rearward wall of the receiver body in overlying relation to the outer end of the passage 50, a helical compression spring 61 being engaged about the stem and exerting pressure upon the plunger to engage it yieldably with the face side of the extractor plate.

At the opposed side of the extractor plate, in axial line with the plunger, the plate is engaged by a cylindrical plug member 62, slidably engaged in the bore 51, and which in turn is engaged by the inner end of a lever 63 pivotally mounted in the laterally recessed end 64 of a mounting bracket 65, secured upon the side of the receiver body by means of screws 66, the pivotal connection of the lever with the bracket consisting of a vertically disposed headed pin 67 engaged through registering holes in the bracket and the lever, and which may be readily removed for the purpose of quick disassembly of the lever when desired. In the normal position of the ex-

tractor parts the spring pressed plunger 58 exerts inward pressure upon the extractor plate and the plug member, the plug member in turn pressing the inner end of the lever 63 against the end wall of the bore 51, which being of predetermined depth acts as a limit stop to determine the normal position of the extractor plate. It will be obvious that swinging movement imparted in forward direction to the outer handle end of the lever 63 imparts swinging movement rearwardly to the inner end, and which through the sliding plug member 62 imparts lateral rearward extracting movement to the extractor plate in opposition to the yielding pressure of the plunger 58. Because of the relatively short lever arm at the inner end of the lever and the relatively long handle comparatively little effort is required to impart relatively great extracting force to the extractor plate.

The outwardly projecting end of the extractor plate is engaged with a fulcrum block 68 secured upon the side of the receiver body by means of screws 69, being provided with a pair of vertically spaced fulcrum anvil projections 70-70 engaging the face side of the outer end portion of the extractor plate above and below of a lateral slot 71 provided centrally of its outer end, the fulcrum support provided thereby causing the extractor plate to swing from its outer end as extracting movement is imparted thereto through operation of the lever 63, and whereby relatively large swinging movement is imparted to its cartridge case engaging inner end through a relatively smaller sliding movement of the lever operated actuating plug 62.

Within the slot 71 of the extractor plate there is pivotally connected one end of a link member 72, the pivot connection being provided by means of a readily removable vertically disposed headed pin 73 engaged downwardly through registering holes in the end of the extractor plate and the link. The other end of the link is pivotally connected to one end of the cross head of a T-shaped lever 74 by means of a readily removable headed pin 75, engaged downwardly through registering holes in the T-lever and the link, the other end of the cross head of the T-lever being pivotally connected to the extractor lever 63 by means of a shouldered pivot screw stud 76 secured to the extractor lever at a point outwardly spaced from its pivotal connection with its supporting bracket. The outer end of the T-lever is provided with a vertically upstanding handle 77, for convenience in manipulating it in cooperation with the manipulation of the lever 63, as will presently more fully appear. The T-lever and its link connection with the extractor plate is adapted to impart projecting and retracting movement to the extractor plate to engage and disengage it with the cannelure groove of the cartridge case, the connection of the T-lever with the lever 63 being such that in either position of the lever 63, that is in its normal position, as indicated in Fig. 5, or in its manually actuated position to impart swinging extracting movement to the extractor plate, as indicated in Fig. 6, projecting and retracting movement may be imparted to the extractor plate along a substantially straight line of pull without binding and without component movements in opposition to the swinging movement of the extractor plate.

In the operation of the device, the cartridge is inserted in the cartridge chamber, with the breech block in its lowered open position, as shown by the dot-and-dash lines in Fig. 1, and

the extractor plate in its retracted position, as shown by the dot-and-dash lines in Fig. 5. The extent of the outward retracting movement of the plate is determined by engagement of the inner end of the slot 56 with the end of the key rib 57 of the plunger 58, so that in the retracted position the inner end of the extractor plate is entirely out of register with the cartridge chamber. After insertion of the cartridge, the breech block is closed and through movement of the T-lever 74 from the dot-and-dash line position to the full line position as shown in Fig. 5, the extractor plate is moved inwardly to its projected position to engage the cannelure groove of the cartridge case. The universal receiver is then fired in the usual manner by pulling of the lanyard 47 of the firing mechanism. Thereupon, following the opening of the breech block, the extractor lever 63 is actuated to impart swinging extracting movement to the extractor plate, as shown in Fig. 6, the cartridge case being thereby extracted from its tight fit in the cartridge chamber. While still holding the lever 63 in its extracting position, the T-lever 74 is actuated to move the extractor plate from its projected to its retracted position, as indicated by the dot-and-dash lines in Fig. 6, whereupon the cartridge case which is now loose and projected from the chamber may be readily removed from the receiver by hand. Upon release of the extractor lever 63, with the extractor plate in its retracted position, the spring pressed plunger 58 moves the extractor plate, the plug 62 and the extractor lever to their normal positions, as indicated in Fig. 5, with the extractor plate in the retracted position shown by the dot-and-dash lines, so that the parts are in position for reloading the receiver.

In Figs. 12 and 13 there is illustrated the .30 caliber barrel 20^a, adapted for use in the receiver 40 interchangeably with the .50 caliber barrel illustrated, or with barrels of other calibers, its end portion 22^a being provided with a milled out slide way 48^a of stepped form, so that the base of the outer portion of the slot is of corresponding depth 45 to the slot 48 of the .50 caliber barrel, while the inner portion adjacent the chamber entrance is of decreased depth to correspond to the smaller dimension of the head of the .30 caliber cartridge. In Figs. 14 and 15 there is shown the extractor 50 plate for cooperation with the .30 caliber barrel, this plate 53^a being provided at its inner end with a reduced height and reduced thickness end portion having a semi-circular recess 55^a in its end shaped to conform to the grooved head of the .30 caliber cartridge case. The face side of the extractor plate is in one plane, while the opposed side is inwardly offset at the inner end portion by means of a semi-circular shoulder 56^a, which fits slidably within the stepped slideway 48^a of the .30 caliber barrel. For other calibers the recessed end of the extractor plate is designed to conform to the cartridge head, the slideway in the barrel end being provided to slidably receive it.

In order to quickly and conveniently change 65 the receiver from one caliber to another, the plunger 58 is retracted to disengage its key rib 57 from the slot 56 of the extractor plate, and is preferably retained in retracted position, during removal of one extractor plate and assembly of the other, by means of a retaining pin 78 inserted through a transverse hole 79 provided in the stem 59 of the plunger near its outer end, this pin being preferably connected by a cord or chain 80 with a screw ring member 81, adapted 75 to be screwed into a threaded socket 82 provided

in the end of the plunger stem for convenience in retracting the plunger. This ring is normally removed from the plunger, so that the latter can not be readily retracted, except through the use of the screw ring or some similar device screwed into the socket 82. With the plunger in its retracted position, as shown in Fig. 16, the pivot pin 73 is removed to disconnect the link 72, whereupon the extractor plate is free and may be readily withdrawn from the receiver. After changing the barrels, the interchangeable extractor plate of the proper caliber is assembled by inserting it in the passage 48 and connecting the link 72 to its outer end by means of the pin 73, whereupon the spring pressed plunger 58 is released by removal of the retaining pin 78, the key rib 57 engaging the slot 56 of the extractor plate and pressing the parts to their normal operative positions.

The form of the invention illustrated in the drawings and described herein is typical and illustrative only, and it is evident that the invention is capable of embodiments in other forms, all falling within the scope of the appended claims, which are to be broadly construed.

What is claimed is:

1. In a firearm, a receiver having a breech opening, a removable barrel carried by said receiver having a cartridge receiving chamber open to said breech opening, a removable extractor member movably carried by said receiver constructed and arranged for movement substantially transverse to the longitudinal axis of said chamber into and out of engagement with the cannelure groove of a cartridge engaged in said chamber and for movement substantially parallel to the longitudinal axis of said chamber to impart extraction movement to the cartridge, actuating means movably carried by said receiver for cooperation with said extractor member to impart cartridge engaging and disengaging and extraction movement thereto, and removable connection means between said actuating means and said extractor member to enable removal and selective interchange of a plurality of such extractor members.

2. In a firearm, a receiver having a breech opening, a barrel carried by said receiver having a cartridge receiving chamber open to said breech opening, an extractor plate member having a recess and movably carried by said receiver, said plate member being freely supported for movement substantially transverse to the longitudinal axis of said chamber into and out of engagement with the cannelure groove of a cartridge engaged in said chamber and for movement substantially parallel to the longitudinal axis of said chamber to impart extraction movement to the cartridge, spring pressed plunger means carried by said receiver, said plunger means having a rib engaged in the recess of said extractor plate member to exert pressure thereon in opposed direction to direction of extraction movement of said plate member and to positively limit the transverse movement of said plate member, and actuating means movably carried by said receiver for cooperation with said extractor plate member to impart cartridge engaging and disengaging and extraction movement thereto.

3. In a firearm, a receiver having a breech opening, a removable barrel carried by said receiver having a cartridge receiving chamber open to said breech opening, a removable extractor plate member movably carried by said receiver con-

structed and arranged for movement substantially transverse to the longitudinal axis of said chamber into and out of engagement with the cannelure groove of a cartridge engaged in said chamber and for movement substantially parallel to the longitudinal axis of said chamber to impart extraction movement to the cartridge, spring pressed plunger means carried by said receiver engaged with said extractor plate member to exert pressure thereon in opposed direction to direction of extraction movement of said plate member, actuating means movably carried by said receiver for cooperation with said extractor plate member to impart cartridge engaging and disengaging and extraction movement thereto, removable connection means between said actuating means and said extractor member to enable removal and selective interchange of a plurality of such extractor members, and retaining means engageable with said plunger means to retain it out of engagement with said plate member while said extractor members are being interchanged.

4. In a firearm, a receiver having a breech opening, a barrel carried by said receiver having a cartridge receiving chamber open to said breech opening, an extractor plate member movably carried by said receiver constructed and arranged for movement substantially transverse to the longitudinal axis of said chamber into and out of engagement with the cannelure groove of a cartridge engaged in said chamber and for movement substantially parallel to the longitudinal axis of said chamber to impart extraction movement to the cartridge, spring pressed plunger means carried by said receiver engaged with one side of said extractor plate member to exert pressure thereon in opposed direction to direction of extraction movement of said plate member, a movement imparting plug member carried by said receiver and engaged with said extractor plate member at the opposed side from said plunger member, and an actuating extractor lever member pivotally mounted upon said receiver and engaged at one end with said plug member to impart extraction movement therethrough to said extractor plate member.

5. In a firearm, a receiver having a breech opening, a barrel carried by said receiver having a cartridge receiving chamber open to said breech opening, an extractor plate member movably carried by said receiver constructed and arranged for movement substantially transverse to the longitudinal axis of said chamber into and out of engagement with the cannelure groove of a cartridge engaged in said chamber and for movement substantially parallel to the longitudinal axis of said chamber to impart extraction movement to the cartridge, an actuating lever pivotally carried by said receiver for cooperation with said extractor plate member to impart extraction movement thereto, and a second actuating lever pivotally carried by said receiver and connected to said extractor plate member to impart substantially transverse cartridge engaging and disengaging movement thereto.

6. In a firearm, a receiver having a breech opening, a barrel carried by said receiver having a cartridge receiving chamber open to said breech opening, an extractor plate member movably carried by said receiver constructed and arranged for movement substantially transverse to the longitudinal axis of said chamber into and out of engagement with the cannelure groove of a cartridge engaged in said chamber and for movement substantially parallel to the longitudinal

axis of said chamber to impart extraction movement to the cartridge, an actuating lever pivotally carried by said receiver for cooperation with said extractor plate member to impart extraction movement thereto, a second actuating lever pivotally mounted upon said first actuating lever outwardly of its pivot axis, and a link connection between said second actuating lever and the outer end of said extractor plate member whereby swinging movement of said second actuating lever imparts cartridge engaging and disengaging movement to said extractor plate.

7. In a firearm, a receiver having a breech opening, a barrel carried by said receiver having a cartridge receiving chamber open to said breech opening, an extractor plate member movably carried by said receiver constructed and arranged for movement substantially transverse to the longitudinal axis of said chamber into and out of engagement with the cannelure groove of a cartridge engaged in said chamber and for pivotal movement substantially parallel to the longitudinal axis of said chamber to impart extraction movement to the cartridge, an actuating lever pivotally carried by said receiver for cooperation with said extractor plate member to impart extraction movement thereto, a fulcrum block member carried by said receiver for supporting engagement with the outer end of said extractor plate whereby the pivotal movement thereof imparts extraction movement to its inner end, said extraction movement being substantially parallel to the longitudinal axis of said chamber, a second actuating lever pivotally mounted upon said first actuating lever outwardly of its pivot axis, and a link connection between said second actuating lever and the outer end of said extractor plate member whereby swinging movement of said second actuating lever imparts cartridge engaging and disengaging movement to said extractor plate.

8. In a firearm, a receiver having a breech opening, a barrel carried by said receiver having a cartridge receiving chamber open to said breech opening, an extractor plate member movably carried by said receiver constructed and arranged for movement substantially transverse to the longitudinal axis of said chamber into and out of engagement with the cannelure groove of a cartridge engaged in said chamber and for movement substantially parallel to the longitudinal axis of said chamber to impart extraction movement to the cartridge, spring pressed plunger means carried by said receiver engaged with one side of said extractor plate member to

exert pressure thereon in opposed direction to direction of extraction movement of said plate member, a movement imparting plug member carried by said receiver and engaged with said extractor plate member at the opposed side from said plunger member, an actuating lever pivotally carried by said receiver and engaged at one end with said plug member to impart extraction movement therethrough to said extractor plate member, a second actuating lever pivotally mounted upon said first actuating lever outwardly of its pivot axis, and a link connection between said second actuating lever and the outer end of said extractor plate member whereby swinging movement of said second actuating lever imparts cartridge engaging and disengaging movement thereto.

9. In a firearm, a receiver having a breech opening, a barrel carried by said receiver having a cartridge receiving chamber open to said breech opening, an extractor plate member movably carried by said receiver constructed and arranged for movement substantially transverse to the longitudinal axis of said chamber into and out of engagement with the cannelure groove of a cartridge engaged in said chamber and for pivotal movement substantially parallel to the longitudinal axis of said chamber to impart extraction movement to the cartridge, spring pressed plunger means carried by said receiver engaged with one side of said extractor plate member to exert pressure thereon in opposed direction to direction of extraction movement of said plate member, a movement imparting plug member carried by said receiver and engaged with said extractor plate member at the opposed side from said plunger member, an actuating lever pivotally carried by said receiver and engaged at one end with said plug member, a fulcrum block member carried by said receiver for supporting engagement with the outer end of said extractor plate whereby the pivotal movement thereof imparts extraction movement to its inner end, said extraction movement being substantially parallel to the longitudinal axis of said chamber, a second actuating lever pivotally mounted upon said first actuating lever outwardly of its pivot axis, and a link connection between said second actuating lever and the outer end of said extractor plate member whereby swinging movement of said second actuating lever imparts cartridge engaging and disengaging movement to said extractor plate.

FLETCHER C. SPEED.
